J. M. SISKO

END GATE LOCK

Filed March 18, 1924

UNITED STATES PATENT OFFICE.

JOHN M. SISKO, OF NESQUEHONING, PENNSYLVANIA.

END-GATE LOCK.

Application filed March 18, 1924. Serial No. 700,082.

To all whom it may concern:

Be it known that I, JOHN M. SISKO, a citizen of the United States, residing at Nesquehoning, in the county of Carbon and State of Pennsylvania, have invented certain new and useful Improvements in End-Gate Locks, of which the following is a specification, reference being had to the accompanying drawings.

10 This invention relates to end gates and particularly to means for holding and locking end gates in place. The object of the invention is to provide a very simple, readily operated and cheaply made construction of 15 this character which will securely lock the end gate at a plurality of points and hold the end gate in closed position.

My invention is illustrated in the accompanying drawings wherein:—

20 Figure 1 is an end view of a wagon showing my end gate applied thereto, the locking device in locking position;

Figure 2 is a section on the line 2—2 of Figure 1;

25 Figure 3 is a section on the line 3—3 of Figure 1;

Figure 4 is a like view to Figure 3, but showing the gate swung outward.

Referring to these drawings, 10 designates the end gate itself, 11 the side walls of the wagon and 12 the bottom of the wagon. Mounted upon the rear face of the end gate is a bridge piece 13 and pivoted to this bridge piece is a lever 14, this lever having an upwardly and laterally extending handle 15, being curved where it passes beneath the bridge piece and being pivoted thereto as at 16. The lever beyond said curve is bent directly downward and is attached to 35 what may be termed a locking bar 17 which extends transversely across the tail gate or end gate, passing through the guides 19. One side wall 11 is formed with a keeper

20 while the bottom of the wagon is formed with a keeper 21. One end of the locking 45 bar 17 is angularly bent downward as at 22 and is adapted to engage in the keeper 21 while the other end is adapted to engage in the keeper 20. A spring 22 urges the locking bar into its locked position. The operation of this device will be obvious from 50 what has gone before. When the end gate is closed the ends of the locking bar are positioned one within the keeper 20 and the other within the keeper 21 and are held in 55 this position by means of the spring 22 which at its outer end is attached to the end gate in any suitable manner. Normally the end gate is held locked by the spring 22 and when it is desired to unlock the end 60 gate the lever 14 is pressed by means of its handle, thus lifting the locking spring 22 and retracting the opposite end of the bar from the keeper 20. It will be seen that this device is very simple and readily 65 operated.

Having thus described my invention what I claim is:—

The combination of an end gate and a wagon body, one of the side walls of the 70 wagon body having a keeper and the bottom of the wagon body having a keeper, a locking bar, one end of which is angularly bent and adapted to engage in the last named keeper and the other end being adapted to 75 engage in the first named keeper, a lever pivoted upon the face of the end gate and operatively engaged with the bar whereby the bar may be shifted to carry the ends out of engagement with the keeper and a spring 80 holding the locking bar in engagement with the keeper.

In testimony whereof I hereunto affix my signature.

JOHN M. SISKO.
